WORK EQUIPMENT

Harold L. De Lisle, Two Rivers, Wis.

Application January 28, 1935, Serial No. 3,698

6 Claims. (Cl. 155—124)

This invention relates to work equipment comprising, in general, a table, desk or the like and a chair associated therewith for movement parallel thereto. The invention is of particular utility as embodied in a work table for drafting equipment including a tiltable drawing board carried by the table and a light overhanging the board, the light being also adjustable to the position of the chair with respect to the table by being mounted to reciprocate thereon.

The invention consists in the novel arrangement and combination of elements contributing to enhanced comfort and efficiency of the worker, together with simplicity and economy of manufacture.

Other objects and advantages will be apparent from the following description, taken together with the accompanying drawings, in which—

Figure 1 is a side elevational view of one preferred form of equipment embodying my invention;

Figure 2 is a partial front elevational view of the same;

Figure 3 is a somewhat enlarged fragmentary cross-section taken on the line 3—3 of Fig. 2, showing details of construction;

Figure 4 is an enlarged fragmentary longitudinal section taken on the line 4—4 of Fig. 1;

Figure 5 is a similar view taken on the line 5—5 of Fig. 2;

Figure 6 is a partial vertical section through the lamp supporting means taken on the line 6—6 of Figure 2; and

Figure 7 is a partial elevation of the lamp carriage, being a section on the line 7—7 of Figure 6.

Referring in detail to the illustrative construction shown in the drawings, what I refer to generally as a work table is here represented by the drafting desk 10 preferably made of steel and in major part of conventional construction.

As here shown, the desk 10 has mounted thereon a drafting or drawing board 11 pivoted at the front of the desk 10 as at 12 so as to be tiltable at varying angles with respect to the desk for convenience of the draftsman or other worker. A hand-operable screw clamp 13 may be mounted on the desk 10 to clamp the edge 14 of a bracket 15 supporting the drawing board 11 and thus secure the board in its selective adjustable positions.

Associated with the desk 10 for parallel movement with respect thereto, I have shown the stool or other chair 16. In accordance with the present embodiment of my invention, the chair includes a seat 17 which may be padded as desired and a

back-rest 18 preferably similarly padded. The seat and back-rest are here shown supported by legs 19. Each leg 19 is pivoted as by the pivot pin 20 to one of the horizontal struts 21 of the chair base 22. The legs 19 are provided with vertically aligned holes 19a and the struts 21 with horizontally spaced holes 21a so that the location of the pivot pins or bolts 20 may be altered as desired to adjust the chair 16 to different heights, and toward or away from the desk 10. The legs of the standard 19 are desirably elongated both for the purpose of elevating the seat 17 to a suitable height appropriate to the height of the drafting board 11 and also for the purpose of providing a substantially long lever-arm for the advantages later pointed out.

The standard 19 and the base 22 may be advantageously formed of tubular steel material for strength, convenience of construction and attractiveness of appearance, and may be enameled or otherwise decorated in a color, for example, to match the color of the desk 10. Thus the legs 19 are pivoted for movement on the base, toward and away from the desk 10, to suit the convenience of the worker. To limit movement of the standard 19, as just described, I may provide a pair of stop bars 29 and 30. The bar 29 is held at one end of the normal arc of rotation of the standard 19, as by being carried by brackets 31 shown in this instance as continuations of feet 32 of the base 22. Location of the bar 29 may be varied from front to rear by being received selectively in notches 23 in the brackets 31 (see Fig. 3). A spring 27 housed in one or both of the brackets 31, keyed at one end as at 28 to the base frame 22 and at the other end as at 29a to the sliding rod 30, is arranged to be placed under tension as the standard 19 is tilted forward from the vertical position shown in full lines in Fig. 1 to an alternative position nearer the desk 10 such as indicated by the broken lines of Fig. 1. The rod 30 slides in slots 24 in the brackets 31 and when the weight of the user is taken off the chair it is retracted by the rearward pull of the rod 30 on the legs 19 (see Fig. 4). Rod 30 is of a diameter sufficient to ride over the notches 23. So constructed and arranged, the worker may lean forward toward the desk when desiring closer access thereto, the seat 17 moving forward with him and adjusting itself automatically to the movement of his body, whereupon when he leaves the seat, spring 27 automatically restores it to its normal position. Rod 29 has reduced ends which are received in the narrow portions of the notches 23, the rod being removable by raising one end thereof so that the reduced portion of

the bar passes out of engagement with the narrow portion through the larger portion of the notch.

Further in accordance with the present embodiment of my invention, the base 22 of the chair 16 is mounted on rollers or other anti-friction means for movement as a whole rectilinearly with respect to the desk 10 and at a fixed distance from the desk. For this purpose, I have shown the feet 32 terminating in preferably rubber-tired wheels 33 suitably journaled to each of the feet 32 as at 34, these wheels resting for rolling contact on the floor 35 spaced apart in a common plane, fixed, as next described, with respect to the desk 10 and parallel thereto. For connecting the chair to the desk to permit this movement in a fixed plane, I desirably provide that the struts 21 of the base 22 extend toward the desk and each terminates in rollers 34 and 35 which are rollingly received in a box-like foot rest 36 which forms somewhat of a parallelogram with the base struts 21 and vertical flange of the base brace 25. The foot rest 36 may be a steel channel bar telescoping over the rollers 34, 35 and extending along the front of the desk 10 parallel with the plane of movement of the chair and affixed to the desk as by screws 38 or the like. The foot-rest 36 may be formed with one angular part 39 having a horizontal surface 40 upon which run the rollers 35 suitably axled to the struts 21 as at 37 on a horizontal axis, the rollers 35 thus having contact by gravity upon the track 40 and being adapted to roll upon the surface 40 thereof in a plane parallel with the wheels 33. To maintain the rollers 35 from running off the track 40 and in a fixed plane with respect thereto, I may provide the other pair of rollers 34 one at each end of the struts 21 and suitably journaled thereon as at 43 upon a vertical axis, each of the rollers 34 extending beneath the top of the member 36 and contacting the lateral walls 44 and 45 of the run-way formed in this instance by an angle-bar 46 constituting a part of member 36. Thus the two rollers 35 may rollingly support the weight of the chair 16 at its forward end, and the two rollers 34 maintain the chair at a fixed distance from the desk 10 in its movement with respect thereto.

My improved work equipment in its illustrative embodiment as a drafting table also desirably includes a light such as the electric lamp 51 carried by desk 10 for movement similar to that of the chair 16. As here shown the lamp 51 is shown carried by the adjustable arm 52 through which passes the insulated conductor 52a, and this arm is in turn attached to a carriage 53 movable along a track 54 secured to the upper rear edge of the drawing board 11 as by screws 55 best shown in Fig. 5. The carriage 53 has a pair of wheels 56 journaled to the carriage 53 on a horizontal axis as at 57 and which are held to their engagement with the track 54 by vertically axled rollers 58 which contact the lateral walls 59, 60 of the channeled member 61 which rollingly encloses these rollers and is a functional part of the track 54 being suitably secured to the part 54a thereof.

The arm 52 passes rotatively through a bracket 62 fixed to the carriage 53 and terminates in a collar 61 which is pressed by a spring 65 against a shouldered portion 63 also fixed to the carriage 53, the spring 65 being compressed between the bracket and the collar to provide the desired friction on turning the arm 52.

So constructed and arranged, the draftsman may, without moving from his seat, roll the chair

16, by a slight pressure upon the desk 10, from side to side of the desk as the necessities of his work upon the drafting board may dictate, and at the same time he may move the seat nearer the drawing board to suit his convenience. At the same time, when he leaves the chair, it remains at a predetermined distance from the desk and is always in position for immediate use being, in fact, practically a unitary part of the desk. Furthermore, as he moves the chair from side to side he may also similarly move the lamp 51 or, if he wishes to stand while working, he may move the lamp to one side of the desk (as shown in broken lines in Fig. 2) and roll the chair out of his way to the other side.

It will be noted that by the construction described, the track is supported by the desk thus leaving the floor in the vicinity of the chair wholly unobstructed except by the chair base itself. Also the chair base has only four legs including the two which are carried on the track by a cantilever action support.

Obviously, the invention is not limited to details of construction shown for purposes of exemplification. Furthermore, it is not indispensable that all features of the invention be used conjointly, as various combinations and sub-combinations may be advantageously employed.

Such changes may be made as fall within the scope of the appended claims without departing from the invention.

Having described my invention, I claim:—

1. In drafting equipment of the class described, the combination including a work table, a track carried by and suspended on said table along the front thereof parallel with the bottom of the table and spaced thereabove, a chair base associated with the table and having a horizontal strut carrying a roller engageable with said track to run thereon and a vertical foot rigid with the strut having a roller engageable with a floor or the like whereby the floor is wholly unobstructed except by the chair base itself in the region thereof, said track comprising a box-like channel bar receiving a plurality of rollers carried by the strut, one of said rollers being horizontally axled to movably support the strut on the track and the other roller being vertically axled and engaging a pair of vertical walls in the channel to prevent substantial movement of the strut away from the track.

2. In drafting equipment of the class described, the combination including a work table, a track supported on said table along the front thereof parallel with the bottom of the table and spaced thereabove, a chair base associated with the table and having horizontal struts carrying a pair of rollers engageable with said track to run thereon and a pair of vertical feet rigid with the struts each having a roller engageable with a floor or the like, said chair base being otherwise unsupported, said track comprising a box-like channel bar receiving a plurality of rollers carried by each strut, one of said rollers being horizontally axled to movably support the strut on the track and the other roller being vertically axled and engaging a portion of the bar to prevent substantial movement of the strut away from the track, said portion of the bar engaged by the vertically axled roller being of inverted channel formation and said roller being received between the downwardly directed flanges of this channel, the upper outer surface of the said portion forming a foot-rest extending along the front of the table parallel with and above the track.

3. In drafting equipment of the class described, the combination including a work desk, a track carried by said desk along the front thereof parallel with the bottom of the desk and spaced thereabove, a chair base associated with the base and having a pair of horizontal struts each carrying a roller engageable with said track to run thereon and a vertical foot rigid with each strut having a roller engageable with a floor or the like, a fixed brace connecting said pair of struts, a bracket extending upwardly of each strut, a removable bar extending between the brackets adjustable toward and from the desk, a standard pivoted on the base and swingable between the said bar and the desk toward and away from the latter, said standard carrying a seat, and means actuated by movement of the standard toward the desk for retracting the standard toward said bar.

20 4. In drafting equipment of the class described, the combination including a work desk, a track carried by said desk along the front thereof parallel with the bottom of the desk and spaced thereabove, a pair of horizontal struts each carrying a roller engageable with said track to run thereon, a vertical foot rigid with each strut having a roller engageable with a floor or the like, a fixed brace connecting said struts, a bracket extending upwardly of each strut, a removable bar extending between the brackets adjustable toward and from the desk, a standard pivoted on each strut, a seat carried by the standards, said seat and standards being unitarily swingable between the said bar and the desk toward and away from the latter, and spring means for retracting the standards toward the bar as an abutment.

5. In equipment of the class described, the combination including a table, a chair base associated with the table, a track for the chair base along the table front providing a guide for parallel movement of the chair base with respect to the table at a uniform distance therefrom, said track being carried solely by the table spaced upwardly from the floor, anti-friction means carried by the chair base and bearing on the track supporting the chair base and permitting said movement of the base, said chair base having at least three points of support being supported on the floor at a point spaced from the table and being otherwise unsupported except by a cantilever support on said track, and a seat carried by the base and movable on the base toward and from the table.

6. In work equipment of the class described, the combination including a work table, a chair base associated with the table, a track for the chair base along the table front providing a guide for parallel movement of the chair base with respect to the table at a uniform distance therefrom, said track being carried solely by the table spaced upwardly from the floor, anti-friction means carried by the chair base and bearing on the track supporting the chair base and permitting said movement of the chair base, said chair base having at least two points of support in a single plane spaced from the table and being otherwise unsupported except on said track, and a seat pivotally carried by the base on a substantially long lever arm for tilting the seat on the base from a vertical position toward the table independently of the relative movement of the base and table.

HAROLD L. DE LISLE.
